UNITED STATES PATENT OFFICE.

DAVID P. DAVIES, OF RACINE, WISCONSIN, ASSIGNOR TO J. I. CASE THRESHING MACHINE COMPANY, OF RACINE, WISCONSIN, A CORPORATION.

TRACTION ENGINE.

1,402,922.

Specification of Letters Patent. Patented Jan. 10, 1922.

Application filed November 3, 1917. Serial No. 200,037.

To all whom it may concern:

Be it known that I, DAVID P. DAVIES, a citizen of the United States, residing at Racine, in the county of Racine and State 5 of Wisconsin, have invented certain new and useful Improvements in Traction Engines, of which the following is a specification.

In the construction of traction engines of the internal combustion motor type, it is 10 customary to build a supporting frame comprising several sections which must be accurately machined, and fitted, and secured together by a large number of bolts, and, in order to obtain the requisite rigidity of such

15 an assembled structure, it is necessary to stiffen and brace the frame by numerous communicating supports, trussed arrangements and the like, but it is well known in actual field work that because of the tremendous strain to which such tractors are 20 subjected, especially when pulling several plows, hauling heavy threshing machinery and the like, these frames undergo a racking strain, often producing such distortion of 25 the structure as to affect the proper alignment and operation of the power mechanisms forming part of the tractor, and, therefore, rendering the same short lived.

The object of my present invention is to 30 produce a tractor, the body or frame of which shall preferably be composed of a single metal casting, and so designed as to include the radiator support, the motor crank case, transmission casing, rear axle 35 housing, and other supporting parts, which unitary structure is highly desirable, especially in the construction of small tractors, and the cost of production of which is materially reduced. I thus completely dispense 40 with the employment of bolts for assembling these various containing and supporting elements into a component frame, and entirely eliminate the necessity of machining, drilling and accurately fitting and precisely alining such parts, thus producing 45 an inflexible and absolutely rigid structure with which the carrying wheels, transmission mechanisms, motor and other elements requisite to a complete tractor may be readily assembled and secured in a comparatively simple and expeditious manner and in positive alinement. While I am enabled to readily produce a single casting for small 50 sized tractors, it will be understood that a 55 product of this character much larger in

proportion and weight for large sized tractors is more difficult, and the liability of loss through breakage or defective castings in molding is much greater, and particularly so when the formation is of substantially the design disclosed herein, which embodies a downwardly inclined radiator support and axle bearing. Therefore, I find it exceedingly practicable to produce large 60 sized tractor bodies in two pieces, which simplifies the casting process and obviates the liability of breakage and defectiveness referred to. In carrying out this method, however, I do not depart from the essential principle embodied in the single casting for 65 small tractors, for I retain and include in a single casting a plurality of compartments comprising the motor crank case, transmission casing, and rear axle housing, and provide for the support of the necessary co-acting power mechanisms communicating therewith from which the propelling and driving power is derived, so that the structure containing these elements is absolutely 70 inflexible and insures positive alinement of these parts in a similar manner to that of the smaller tractor body. The second or forward section of the body which supports the radiator and front wheels is preferably 75 a single casting, which, when secured to the main casting, produces in effect a rigid body of substantially the character first herein referred to, but this portion of the body carries no parts requiring exact or positive alinement, being adapted for supporting the 80 radiator and forward carrying wheels.

In the accompanying drawings, which form a part hereof, Figure 1 is a plan view of a tractor embodying my improved frame, showing assembled therewith the carrying 95 wheels and the various power mechanisms and accessories common to tractors; Fig. 2 a side elevation of said frame; Figs. 3 and 4 detail sectional views; Fig. 5 a side elevation; Fig. 6 an under side plan of the tractor frame, and Fig. 7 a side elevation of said frame in two parts.

As indicated, my improvement relates more particularly to the body or frame of the tractor, which I produce preferably from a 105 single metal casting, but which may comprise two such castings, so formed or arranged as to provide the supports for the various elements necessary for the propulsion and operation of such a structure, and, as shown 110

in the drawings, in which similar letters of reference indicate similar parts, said body or frame, 5, comprises a transversely arranged member, 6, at its forward end for supporting a radiator, as 7. The casting then continues on to the rear end, preferably inclining slightly, at 9, (Fig. 2), after it leaves said member 6 until at its upper side a shelf, 10, is formed for supporting 5 (see Fig. 1) a magneto, 11, water pump, 12, and housing, 13, for enclosing the gears and shaft which supports and drives the fan 8. Where the body comprises two parts, however, the forward portion 9 is securely bolted 10 to part 5, as will be clearly understood by reference to Fig. 7, but the body in its entirety is to all intents and purposes similar to that shown in the other figures of drawing. Between said member 6 and shelf 15 10 said body is hollow, as at 14, by which formation I eliminate a considerable amount of unnecessary weight, at the same time through the depth and thickness of the surrounding walls insuring a strong and rigid 20 structure. At one side of said body I form a support, 15, to which an arm, 16, is secured which communicates with the engine crank shaft and sustains a clutch shifting lever, 17. Behind said shelf 10 the body or 25 frame 5 may be hollowed, or preferably open from bottom to top, and of a suitable formation to receive a crank shaft, 18, serving as a compartment therefor. Any suitable motor such as the engine, 20, as will 30 be readily understood, may be placed in position above and connected to said crank shaft 18, the formation of the upper side of the body 5 being such as to constitute an engine base, 21, to which the engine may 35 be fixedly secured by bolts or otherwise, in a well known manner. The lower ends of walls, 22, within which the crank shaft is mounted, are flanged, as at 23, and to which I secure by bolts, 24, a splash tray, 25, 40 comprising a top having depressions, 26, therein through which the cranks of the shaft pass when in operation, the bottom of said tray comprising a plate, 27, having a drip, 28, therein, which plate may be secured to the flanged walls 23 by the bolts 24 as indicated. By this simple construction the tray as a unit may be removed and replaced readily, and thus access can be had 45 to the crank shaft, pistons, cylinders and other parts comprising the motor. While I have shown the crank shaft case of a formation to receive a transversely arranged shaft, it will be understood, of course, that the same may be modified in form so as to accommodate a shaft positioned longitudinally 50 of the tractor body, or at right angles to the transmission shafts. Behind the crank case described the body has a hollow formation 55 constituting a compartment or casing, 30, for the accommodation of the transmission 60 shafts and associated mechanisms, the bearings for said shafts being reinforced by integral flanges, as 31, 32, forming part of the body 5, and from this chamber the body extends to and terminates in a compartment 70 or housing, 35, for the rear axle, 36, said housing at its outer ends being flanged, at 37, 38, to constitute bearings for said axle, and in proximity to said housing I extend lugs 36', 37', 38', which may be suitably 75 drilled for the attachment of parts communicating with the structure generally. As shown, I prefer to form said rear axle housing substantially barrel-shaped, thus providing an oil chamber for said axle, at 80 one side of which is mounted the differential, 39, which communicates with the second transmission shaft, 40, through gears is a well known manner. The transmission mechanisms in compartments 30 are enclosed and protected by a suitable cover, as 85 41, which may be bolted or otherwise secured to the body. As will be understood, of course, the bottom of transmission compartment 30 need not be an integral part 90 of the structure, and particularly so where a large and heavy casting is produced, in which case both the upper and lower side of the compartment may be open, to thus facilitate the work of casting, and which 95 openings may be closed by the covers 41 and 42. The carrying wheels 50, 51, may be of any suitable construction for the purpose, and I prefer to mount the forward wheels 50 on an axle, 52, which is pivotally mounted, as at 53, in advance of the body, thus obtaining a three-point support for the tractor body and eliminating the racking or twisting strain thereof, and on the under side of said body I include a support, 55, to 100 which a drawbar, 56, may be bolted.

I have not specifically detailed all of the parts shown, as many of them are common and well known, and make no claims therefor, but, as hereinbefore indicated, my improvement comprises essentially a tractor body or frame formed preferably in one continuous piece of metal embodying a plurality of compartments, or in two pieces bolted together when the body is of a large and 110 weighty character, and so proportioned and designated as to constitute and provide for the support of the various elements requisite to a complete tractor, thus entirely eliminating the necessity for separately constructing such supports, then machining and accurately assembling the same in a frame, and alining and bolting them. I thus produce a rigid and stiff structure upon and within which all the operating mechanisms may be 115 readily and accurately assembled without the possibility of non-alinement of the shafting or other power producing parts, and which in operation in the field will be free 120 from vibration and distortion and the rack- 125 130

ing strain to which a tractor frame made in several sections is subjected, and also a tractor the rotary and delicate mechanisms of which will be enclosed and protected from 5 dust and other extraneous matter.

I claim as my invention:

1. In a traction engine, a body portion comprising a continuous integral steel casting embodying a motor supporting base and 10 formed to accommodate a system of shafts forming part of the driving mechanisms all of which shafts are arranged in parallel relation with each other and lie transversely of the frame, said frame being formed with 15 a downwardly extending front end embodying a radiator support and its rear end embodying a rear axle housing, all substantially as set forth.
2. A body for traction engines comprising 20 a continuous integral casting formed at its upper side with a shelf for supporting operating parts, with a motor supporting base adjacent to said shelf, with a compartment beneath said motor supporting base, 25 and with an open compartment for the

transmission mechanism adjacent to said motor supporting base with a top therefor, the surfaces of said several parts on which the operating mechanism, the motor and the cover for the last mentioned compartment 30 are mounted being formed in the same plane, whereby they may be planed or machined at a single operation, substantially as set forth.

3. A traction engine body comprising a 35 continuous integral casting having formed therein supports and bearings for the various operating parts to be carried thereby, including bearings for the crank-shaft, transmission mechanism, axle housings, 40 etc., the outer ends of which are formed to extend into the same plane, whereby they may be dressed or machined at a single operation, substantially as set forth.

In testimony whereof I affix my signature 45 in the presence of two witnesses.

DAVID P. DAVIES.
